WATER HEATER CASING

Alan W. Duncan, Itasca, Ill.

Application July 12, 1954, Serial No. 31,384

Term of patent 7 years

(Cl. D81—2)

To all whom it may concern:

Be it known that I, Alan W. Duncan, a citizen of the United States, residing at Itasca, in the county of Du Page and State of Illinois, have invented a new, original, and ornamental Design for a Water Heater Casing, of which the following is a specification, reference being had to the accompanying drawing, forming a part hereof.

Fig. 1 is a front elevational view of a water heater casing embodying my new design;

Fig. 2 is a side elevational view of the same; and

Fig. 3 is a top plan view thereof.

The side not shown is similar to the side shown in Fig. 2.

The back is plain.

I claim:

The ornamental design for a water heater casing, as shown and described.
